DESIGN FOR A COOKING STOVE

William H. Stangle, Evansville, Ind., assignor to
Servel, Inc., New York, N. Y., a corporation of
Delaware

Application November 7, 1941, Serial No. 104,084

Term of patent 14 years

To all whom it may concern:

Be it known that I, William H. Stangle, a citizen of the United States of America, residing at Evansville, in the county of Vanderburgh and State of Indiana, have invented a new, original, and ornamental Design for a Cooking Stove, of which the following is a specification, reference being had to the accompanying drawing, forming part thereof.

The figure is a perspective view of a cooking stove showing my design.

The end of the stove not seen in the drawing is substantially like the end which is shown.

I claim:

The ornamental design for a cooking stove, as shown and described.

WILLIAM H. STANGLE.
